UNITED STATES PATENT OFFICE

ROE P. HENDERSON, OF SPRINGFIELD, OHIO, ASSIGNOR TO THE SPRINGFIELD METALLIC
CASKET COMPANY, OF SPRINGFIELD, OHIO, A CORPORATION OF OHIO

DESIGN FOR A CORNER FOR BURIAL CASKETS

Application filed October 13, 1930. Serial No. 37,249. Term of patent 14 years.

To all whom it may concern:

Be it known that I, ROE P. HENDERSON, a citizen of the United States, residing at Springfield, in the county of Clark and State of Ohio, have invented a new, original, and ornamental Design for Corners for Burial Caskets, of which the following is a specification, reference being had to the accompanying drawing, forming part thereof.

In the accompanying drawing:

The figure is a front perspective view of a corner for burial caskets, showing my new design.

I claim:

The ornamental design for a corner for burial caskets, as shown.

ROE P. HENDERSON.
